United States Patent

Des. 236,750
Patented Sept. 9, 1975

236,750

REFUSE PACKER

Stanley W. Worthington, 824 Clough,
Waterloo, Iowa 50701

Filed May 24, 1973, Ser. No. 363,518

Term of patent 14 years

Int. Cl. D15—99

U.S. Cl. D55—1 B

FIG. 1 is a perspective view of a refuse packer in accordance with my new design;

FIG. 2 is a top plan view thereof;

FIG. 3 is a front elevational view thereof with the legs in an alternate position;

FIG. 4 is a side elevational view thereof with the legs in an alternate position, the other side being a mirror image thereof; and

FIG. 5 is a rear elevational view thereof with the legs in an alternate position.

I claim:

The ornamental design of a refuse packer, substantially as shown and described.
